FIG. 3

INVENTOR
August R. Lewis
BY
Pierre Barnes
ATTORNEY

UNITED STATES PATENT OFFICE.

AUGUST R. LEWIS, OF KENT, WASHINGTON.

BROODER.

No. 902,889.

Specification of Letters Patent.

Patented Nov. 3, 1908.

Application filed September 4, 1907. Serial No. 391,310.

To all whom it may concern:

Be it known that I, AUGUST R. LEWIS, a citizen of the United States, residing at Kent, in the county of King and State of Washington, have invented certain new and useful Improvements in Brooders, of which the following is a specification, reference being had therein to the accompanying drawings.

10 This invention relates to brooders; and its object is the provision of a device which will be of inexpensive and durable construction, which may be readily adjusted to accommodate young chickens of various sizes, and which will require but little attention on the part of the operator.

15 With the foregoing ends in view the invention consists in the novel construction, adaptation and combination of parts as will be hereinafter described and claimed.

20 In the drawings, Figure 1 is a side elevation of a brooder embodying my invention; Fig. 2 is a longitudinal vertical section of the same, but with the hinged cover portion of the casing and the doors shown in an open condition; and Fig. 3 is a cross sectional view taken through 3—3 of Fig. 1.

25 The brooder proper is comprised of a casing, or box, having a bottom 5, sides 6, a front end 7, a back end 8 and a top 9. In the front end is an opening 7' provided with a hinged door 7''. Said top is formed with an opening adjacent to each of its ends whereby access may be had to the interior of the casing and are provided with closures which are hinged to a transverse bar-member 9' of the top. The closure for the opening 10, which is adjacent to the back end of the casing, is made of two parts 11 and 12, of which the rearmost one is the smaller and is provided with a pane of glass 12'. The closure 13 for the other opening is also provided with a glass pane 13' which is considerably larger than the pane of the closure 12 in order to admit the light to a greater degree toward the head end of the apparatus.

30 Within the casing is a floor 14 adapted to be adjustably supported at various heights and which may be conveniently done by 35 props 15 which are hinged to the casing-bottom and have their free ends tiltably raised or lowered by lines 16 which are attached thereto and about a rotatable rod 17, as illustrated in Figs. 2 and 3. This rod is 40 journaled in the side members of the casing and has an enlarged extremity 17' protrud-

ing outwardly from one of such sides and whereby the turning of the rod is effected. This extremity is provided with peripheral notches 17'' for engagement with a pawl-bolt 18 for securing the rod against rotation and thus maintain the floor, which is supported upon the props, at any adjusted height.

45 Just below the casing top are transverse poles 19 and 20 which are respectively disposed to be in proximity of the door 7' and below the top bar-member 9', and have ends, such as 20'', extended outside of the casing for turning the same in order to raise or 50 lower the curtains 19' and 20' which are rolled about the respective poles. Positioned within the casing and immediately below the closure part 11 is a tank 21 formed with straight side walls 22, a flat cover-plate 75 23, desirably of metal, and a curved bottom 24, formed of a flexible sheet of rubber or equivalent material.

55 25 is a boiler of any appropriate size or shape, but preferably of the type illustrated 80 and comprising an outer cylindrical shell 26 and an inner truncoïdal shell 26' arranged concentric with each other and affording therebetween a space 27 for the heating water which is supplied through an 85 opening 26'' having a cap 28.

60 A pipe 29 makes communication between the top of the boiler water-space and the top of the tank and similar connection is made between the bottoms of these elements by 90 a pipe 30, and by such an arrangement a circulation of water is created in the heating system, as indicated by darts in Fig. 3, when heat is generated by the boiler. The pipes in passing through the casing are supported 95 thereby and in turn sustain the boiler and, ordinarily, the tank by rigidly connecting the adjacent side wall of the latter with the pipes and extending one of the pipes, as 29, 100 to be socketed within a recess 22' in the remote wall. Pipe 29, adjacent its outer end is formed on its top with an opening 29', by means of which the water passing through pipe 29, from the boiler escapes into the tank.

105 In brooders of uncommonly large size, resort may be had to suitable supports supplementary to the pipes, as above explained; however, it is advantageous to extend one of the pipes as shown in order that the intake and delivery of the water will occur at opposite sides of the tank and cause a 110

cross current therein. The water is heated by a suitable heat generator, such as a lamp 31 having its chimney extended into the chamber 32 of the boiler and from this chamber the smoke or other combustion gases are led away by a tubular conduit 33 extending to within a short distance of the front end of the casing and thence through and terminating beyond the further side of the latter.

Where the conduit enters the casing an annular space is provided, indicated by 34 in Fig. 1, to furnish a delivery passage for a hot-air tube 35 which surrounds the conduit and reaching from within a short distance of the boiler to its entry to the casing provides thereby a duct for a supply of heated air to the brooder. The smoke conduit imparts heat to the current of air entering said duct and which is ample to maintain the compartment intermediate curtains 19' and 20' at a suitable temperature. Vent holes 36 are provided in the back end of the casing to allow of the escape of the foul 25 gases emanating from the brooder - occupants.

37 represents an under cover of wool or fleecy fabric for the tank bottom to protect the young poultry from coming in direct 30 contact with the relatively hot tank and presenting a comfortable surface to nestle against.

In operation, the boiler is first filled, through the opening 26", with water at a 35 boiling temperature, the lamp is then lighted and all of the casing closures shut. When the brooder becomes heated to a suitable temperature, the chickens are introduced by raising the hinged part 12. Should the floor 40 be found to be improperly adjusted to accommodate the chickens, it may be raised or lowered, as desired, by manipulating the rod 17.

It is found that extremely young broods 45 will, as a rule, remain within the compartment to the rear of the curtain 20' and may be inspected through the glazed closure 12. As the chickens grow, they will pass into the cooler and better lighted compartment 50 at the other side of this curtain and thence, when the external temperature permits, through the opening 7' to the outside. The temperature within the brooder is controlled 55 through regulating the lamp and also the opening of the door 7" and the closures in the casing top.

The invention is well adapted for the purposes for which designed, requiring but little attention, and its action is not subject to 60 rapid changes in the surrounding temperature. The interior of the brooder is accessible for cleaning and its occupants are at all times capable of being inspected.

What I claim is,—

65 1. In a brooder, the combination of a tank

positioned interiorly of the brooder-casing, a boiler positioned outside of the casing, pipe connections between the upper and lower portions of the tank with corresponding parts of the boiler, a lamp for generating heat within the boiler, a conduit leading from said lamp through the casing, and a tube surrounding said conduit and spaced therefrom having one end extending in the casing and the other end open to the atmosphere.

2. In a brooder, a casing, a tank adjacent one end thereof, a central partition in said casing, means to heat water in said tank, a conduit having connection with said heating means and extending across the opposite end of said casing, on the interior thereof to provide heat for the latter, and an air pipe surrounding said conduit and spaced therefrom, said air pipe having its outer end located on the exterior of the casing and being open and disposed adjacent said heating means and having its inner end leading into said casing, said conduit heating the air during the passage of the same through said air pipe into said casing.

3. In a brooder, a casing, a tank therein, a partition to one side of the tank, means to heat water in said tank, an air pipe having one end open to the atmosphere and having its opposite end discharging into said casing on the side of said partition opposite to that on which said tank is disposed, and means communicating with said heating means and disposed adjacent to said air pipe for heating the air during its passage through said pipe prior to its entrance into said casing.

4. In a brooder, the combination with the casing, heating means for the brooder, such means comprising a tank within the casing and provided with a flexible bottom wall, a smoke conduit extending through the casing from side to side, a boiler having a chamber connected with said conduit, pipe connections between the tank and the boiler, and a lamp for supplying heat to the boiler.

5. In a brooder, the combination with the casing, and a curtain, of heating means for the brooder, such means comprising a tank within the casing to one side of said curtain, a smoke conduit extending through the casing at the other side, a boiler having a chamber connected with said conduit, pipe connections between the tank and the boiler, and a lamp for supplying heat to the boiler.

6. In a brooder, the combination with the casing, a vertically movable floor within the casing, and a curtain for dividing the space above said floor into two compartments, of heating means for the brooder, such means comprising a tank within the space to one side of said curtain, a smoke conduit extending through the space at the other side, a boiler having a chamber connected with said conduit, pipe connections between the

tank and the boiler, and a lamp for supplying heat to the boiler.

7. A brooder comprising a casing having openings at the top and at the front end thereof, closures for said openings, a movable floor within the casing, means to raise or lower said floor, a curtain intermediate the length of the casing and dividing the space above the floor into two compartments, 10 means for raising or lowering said curtain, a tank provided with a flexible bottom wall positioned within one of said compartments, a boiler, pipes connecting the upper and lower portions of the tank with the corresponding portions of the boiler, heating means for said boiler, and a tubular smoke conduit from the boiler extending through the compartment of the casing which is unoccupied by said tank.
- 20 8. A brooder comprising a casing having openings at the top and at the front end thereof, closures for said openings, a movable floor within the casing, means to raise
- or lower said floor, a curtain intermediate the length of the casing and dividing the 25 space above the floor into two compartments, a curtain adjacent of the front end of the casing, means for raising and lowering said curtains, a tank provided with a flexible bottom wall positioned within one of said 30 compartments, a boiler, pipes connecting the upper and lower portions of the tank with the corresponding portions of the boiler, heating means for said boiler, a tubular smoke conduit from the boiler extending 35 through the compartment of the casing which is unoccupied by said tank, and a hot-air pipe inclosing a part of said conduit and communicating with the space within the 40 casing.

In testimony whereof I affix my signature in presence of two witnesses.

AUGUST R. LEWIS.
